SLICING MACHINE

Cornelis Franciscus Maria van Berkel, Wassenaar,
Netherlands, assignor to U. S. Slicing Machine
Company, La Porte, Ind., a company of Indiana

Application February 15, 1936, Serial No. 64,149
In Great Britain February 19, 1935

12 Claims. (Cl. 146—102)

This invention relates to slicing machines of the type in which there is provided in association with the slicing knife an abutment whose active face is arranged parallel to and slightly beyond the slicing plane.

An abutment as aforesaid is generally used as a gauge for controlling the slice-thickness, and it is therefore adjustable to-and-from the slicing plane so that slices of any desired thickness can be obtained. In slicing machines having such an abutment, the substance to be sliced is mounted on a support having provision whereby it is or can be fed forward (automatically or manually) after each slice-cutting operation to bring the leading end of the substance against the abutment preparatory to the next slice-cutting operation.

It is also known to use an abutment as aforesaid as a gauge for positioning the substance preparatory to the cutting of a succession of slices.

Abutments such as heretofore in use consist of some form of rigid plate, and a disadvantage of such an abutment is that the substance rubs against the face of the plate as the substance is moved towards and returned from the knife, so that undesirable frictional resistance is caused which adds to the work of operating the machine.

The main object of the present invention is to avoid the aforesaid disadvantage by providing an abutment whose substance-engaging portion is movable in unison with the substance, preferably by the substance itself. In the use of such an abutment, there is substantially no rubbing between substance and abutment, and the work of operating the machine is proportionately reduced.

Another object of the present invention is to provide an abutment consisting of one or more flexible members, such as endless bands, belts or the like.

Yet another object is to provide thrust-resisting means to support the substance-engaging portion of the abutment, particularly when subjected to the pressure of the substance.

Yet another object of the invention is to provide an abutment to be utilized in a slicing machine having slice-stacking mechanism and when so utilized the travelling abutment can be arranged to function as the slice-conveyor of said mechanism and as such to support the slice from the time when it is being cut until the time when it is discharged by the fly. Such an abutment would preferably be provided with small projec-

tions adapted to enter that portion of the substance to be severed as a slice.

The foregoing objects are attained by the combinations of slicing-machine parts which will now be described, by way of example, with reference to the accompanying diagrammatic drawings.

In the drawings:

Fig. 1 is a perspective view of a slicing machine of simple construction having an abutment with a movable substance-engaging face.

Fig. 2 is a sectional elevation, drawn to a larger scale than Fig. 1, showing an assembly of parts of said slicing machine, including the abutment; and Fig. 3 is a section on the line II—II of Fig. 2.

Figs. 4 and 5 are corresponding sections of differently constructed slicing-machine-abutment assemblies.

Fig. 6 is an elevation corresponding to Fig. 2 but showing another differently constructed slicing-machine abutment assembly, and Fig. 7 is a section on the line VII—VII of Fig. 6.

Fig. 8 is a sectional elevation corresponding to Figs. 2 and 6 but showing yet another differently constructed assembly.

Fig. 9 is a fragmentary elevation showing an alternative form of a gauging member.

The slicing machine shown in Fig. 1 comprises mainly the following elements: a stationary base 1; a carriage 2 for the meat or other substance to be sliced; a rotary circular knife 3, which is journaled at one side of the base and may be motor driven; guides 4 on the base, along which guides the carriage can be reciprocated past the knife; a pivotally mounted combined pusher and clamp 5 for feeding the substance across the carriage; an adjustable abutment generally denoted in Fig. 1 by 6, said abutment being herein-after described, said abutment functioning in the construction shown as a gauge for guiding the substance towards the knife in the slicing stroke of the carriage and thus determining the thickness of the slices to be cut from the substance; and a guard plate 7 which masks the knife except the active portion of the edge thereof. A handle 8 on the element 5 serves the dual function of means whereby the operator can reciprocate the carriage and feed the substance across the carriage. The machine's slice receiver is denoted by 9.

The abutment shown in Figs. 1, 2 and 3 consists of several endless flexible bands, or belts, 10 passing around diametrically reduced portions of vertical rolls 11, 12 disposed at opposite ends of the abutment. The front stretches of the bands

10 constitute the substance-engaging portion of the abutment, said stretches together presenting a composite face 10a (Fig. 3) located in a vertical plane extending parallel to the slicing plane 5 of the slicing knife 3.

The rolls 11, 12 are journalled at their ends in a supporting frame consisting of top and bottom members 14, 15 and side members 16, 17. The bottom member is rigidly secured to a horizontal rod 18 and rests upon a guide-support 19. The rod 18 is slidale endwise in known manner under the control of a turnable handle 13, which is marked to indicate various slice-thicknesses. The support 19 is rigidly fixed to the base 10 of the machine. Thus, the arrangement is such that endwise adjustment of the rod 18 results in corresponding adjustment of the face 10a to or from the slicing plane of the knife 3, as indicated by the setting of the handle 13.

20 Since various modes of supporting slicing-machine abutments and various mechanisms for adjusting them to regulate the slice-thickness are known, further illustration and description thereof herein is unnecessary.

25 The side frame member 17 is provided with a flat-faced plate 20 constituting a guide, one side of which is curved in conformity with the knife curvature and the other side of which is formed with spaced lateral projections 20a adapted to fit 30 into the spaces between adjacent bands 10, so that in effect the plate 20 meshes with the abutment. The active face of the plate 20 is arranged in the same plane as that of the face 10a.

Vertical thrust-resisting rolls 21 are also journalled at their ends in the frame members 14, 15, said rolls bearing against both the front and rear stretches of the bands 10.

In operation of a slicing machine equipped with the abutment assembly shown in Figs. 1 to 3, 40 before each slicing stroke commences the substance is fed forwards until the end to be sliced off bears flat against the face 10a. The slicing stroke is horizontal and in the direction of the arrow A, Figs. 1 and 3. Accordingly, the moving substance constrains the front stretches of 45 the bands 10 to move in unison with it during that part of the slicing stroke in which the substance bears against the face 10a. In consequence, rubbing between the substance and the 50 abutment is more or less completely absent, frictional resistance due to the action between the substance and abutment is materially reduced and the work of operating the machine is proportionately reduced.

55 With the object of reducing to a minimum the effort required to turn the rolls 11, 12 and 21, these have been shown journalled in ball bearings 22. If desired, however, any other suitable bearings may be adopted instead.

60 The function of the plate 20 is to guide the substance in the immediate vicinity of the knife, it being impracticable to extend all the bands 10 close to the knife's edge because of the curvature thereof.

65 The function of the rolls 21 is to prevent flexure of the front stretches of the bands 10 under the pressure of the substance.

Various modifications of the construction illustrated in Figs. 1 to 3 can be made. For example, 70 the bands could be dispensed with, the abutment in that event consisting of a series of vertical rolls—preferably much more closely spaced than the rolls 11, 12 and 21—arranged to present a substance-engaging face.

75 In the construction according to Fig. 4, the

thrust-resisting means consists of a stationary plate 23 secured to a frame 24 in which the end rolls 11, 12 are journalled.

In the construction according to Fig. 5, the thrust-resisting means consists of a series of 5 small-diameter vertical rolls 25 bearing against only the front stretches of the bands 10, these rolls being journalled at their ends in a frame 26 in which the end rolls also are journalled.

With reference to Figs. 6 and 7, the abutment assembly therein illustrated is intended to be used with a slicing machine of the type specified having slice-stacking mechanism. Such mechanism comprises a slice-conveyer, means for pressing each successive slice into secure attachment 10 with the conveyer, and a fly for discharging the slice upon a slice-receiver. Since various constructions of such slice-stacking mechanism are known, it is unnecessary to illustrate the same in greater detail than in Figs. 6 and 7. 20

In the application of the abutment assembly to a slicing machine such as aforesaid, the abutment is arranged to function also as the slice-conveyer of the stacking mechanism.

The abutment-conveyer unit shown consists of 25 an endless series of vertical bars or laths 30 to which are secured endless bands 31 arranged one above another. The ends 30a of the bars 30 are formed as shown to engage collars 32, at the ends of vertical rolls 33, and also thrust-plates 34 extending horizontally from collar to collar. These rolls would be journalled at their ends in a frame (not shown) in the manner already described with reference to Figs. 1 to 3. The bands 31 are provided with small sharp projections 35 adapted 35 to enter that portion of the substance which is to be next severed as a slice.

The means for pressing each slice into attachment with the projections consists of the usual guide 36 (Fig. 7) stationarily fixed at the back 40 of the knife edge and provided with horizontal grooves 37 at the levels of the projections 35.

The discharge-fly consists of an arm 38 formed with horizontal fingers 39 and secured to a rock-shaft 40 adapted in known manner to impart 45 a downward and rearward slice-discharging movement to the arm 38 at an appropriately timed instant in each cycle of operations of the machine. The arm 38 prior to its slice-discharging movement stands erect, as shown, with its 50 fingers 39 extending along the spaces between the bands 31.

In operation of the assembly, the substance exercises the same action on the abutment-conveyer unit 30, 31 during the slicing stroke as already described with reference to the abutment according to Figs. 1 to 3, and in addition the slice passing from the knife is pressed by the guide 36 upon the projections 35. The severed slice remains partially between the guide 36 and bands 31 during the machine's return stroke. During the next slicing stroke, the front stretches of the bands are again moved in the direction of the arrow A (Fig. 7) but the already severed slice is conveyed by the rear stretches in the direction of the arrow B into register with the discharge-fly, which would be erect awaiting the oncoming slice to discharge the same from the projections in the usual way upon the slice-receiver (not shown). 65

The construction according to Fig. 8 differs from that just described mainly in that the abutment-conveyer unit consists of a single wide band 41 of rubber or other flexible material.

70 The structure shown in Fig. 9 involves an al- 75

ternative form of stationary guide plate adjacent the edge of the knife. Thus, in place of the plate 20 shown in Fig. 2, for instance, there is provided the surface 20b forming the side of the 5 gauging member adjacent the edge of the knife. Herein the rollers 12, however, are journaled in protruding portions formed in the arm 17, while between each of the members 16 there extends for a short distance the lateral projections 20c 10 which corresponds generally to the projections 28, as shown in the previous embodiment in Fig. 2. The rollers 12 being separately journaled, are axially offset in order to likewise, in effect, situate them also along the arc of a similar circle 15 and, since the projections 20c follow the same arrangement, the entire end of the gauging mechanism is more or less symmetrical with the knife edge and, therefore, presents the substance properly thereto.

20 It is to be understood that the invention has been described in the foregoing specification with reference to the drawings merely by way of example and that its constructional features can be varied within the scope of the following claims 25 without departing from the spirit of the invention therein claimed. For instance, the invention is applicable not merely to slicing machines such as shown in Fig. 1, but to slicing machines in general.

30 I claim:

1. In a slicing machine including a rotary circular knife for cutting a substance into slices, a normally stationary support adjacent said knife, means movably mounted on said support for movement at least towards the knife, said means presenting a face whose plane is substantially parallel to the knife's cutting plane, and a normally stationary guide on said support between said face and the knife and arranged to present 35 a guiding surface substantially co-planar with said face.

2. A slicing machine comprising a rotary circular knife, an abutment adjacent said knife, means for moving a substance past said abutment for cutting by said knife, said abutment comprising a normally stationary support, flexible means movably mounted on said support, said flexible means presenting a substance-engaging face whose plane is substantially parallel 45 to the knife's cutting plane, and a normally stationary guide on said support, said guide extending between said flexible means and the knife and presenting a guide surface in alignment with said face.

50 3. A slicing machine as claimed in claim 2, in which the flexible means therein defined comprises superposed endless flexible members and in which the normally stationary guide is formed to mesh with said members.

55 4. A slicing machine comprising a rotatable knife for cutting a substance into slices, a frame mounted adjacent said knife, means for moving the substance past said frame for cutting into slices by said knife, rolls journaled in said frame, movable endless flexible members supported by said rolls and arranged at different levels one above another, said members presenting to the substance a front face constituting a movable slice-thickness gauge, means to cause substance to abut said slice-thickness gauge and to permit the slices to be gauged thereby, projections on said endless flexible members for engaging the substance and retaining engagement with the slices cut therefrom, and a fly at the rear of said members for discharging slices therefrom, said

60 fly having fingers arranged to extend between said members preparatory to each slice-discharging operation.

5 5. A slicing machine comprising a frame, a stationary rotatable knife mounted in said frame for cutting a substance into slices, a support normally occupying a stationary location adjacent the knife, gauging means movably mounted on said support for movement in a plane generally parallel to that of the knife, means to cause the 10 gauging means to be engaged by the substance to gauge the slice thickness thereof and move with the substance as it passes the support, said frame being provided with a guide-way for the support for guiding the support in a path toward and 15 away from the plane of the knife, and adjusting means associated with the frame and support to permit adjustment of the gauging means.

6. A slicing machine comprising a frame, a rotatable knife mounted on said frame for slicing a substance, an abutment, a carriage mounted on said frame for reciprocating movement across the cutting plane of the knife, said abutment comprising a support located adjacent the knife and having a gauging face generally parallel to the plane of the knife and movably mounted on the support, a guide-way for said support operatively associated with said frame for permitting slidable movement of the support to and away from the cutting plane of the knife, adjusting means associated with the frame and support to permit adjustment of the abutment in predetermined gauging relationship, and feeding means actuatable across the plane of the knife and toward the abutment to permit feeding of the substance on the carriage to contact said substance against the gauging face to gauge the slice thickness whereby to cause the gauging face to move with the substance toward the 30 knife.

35 7. A slicing machine comprising a frame, a stationary rotatable knife mounted for operation in a generally vertical plane, an abutment, a carriage having a generally horizontal supporting surface, said abutment comprising a support located adjacent the knife and having a gauging face generally parallel to the plane of the knife and movably mounted on the support, a guide-way for said support operatively associated with said frame for permitting slidable movement of the support to and away from the cutting plane of the knife, adjusting means associated with the frame and support to permit adjustment of the abutment in predetermined gauging relationship, and feeding means actuatable across the 40 plane of the knife and toward the abutment to permit feeding of the substance on the carriage to contact said substance against the gauging face to gauge the slice thickness whereby to cause the gauging face to move with the substance toward the knife.

45 8. A slicing machine comprising a frame, a rotatable knife mounted on said frame, a gauging abutment, said abutment comprising a support mounted on said frame adjacent said knife for relative and constrained movement to and from the plane of the knife, adjusting means mounted on the frame and operatively connected with the support to permit adjustment of the abutment to and from said plane of the knife, 50 a carriage for supporting the substance for reciprocating movement past said abutment and across the cutting edge of the knife, flexible means movably mounted on said support for relatively free motion in the plane generally par- 55

allel to that of the knife, and feeding means on the carriage for feeding substance in direct abutment with said flexible means to accurately gauge the thickness of the slice and to cause the said substance to frictionally engage the surface of the flexible means and cause said last named means to move with the substance toward the knife during said reciprocatory movement.

9. A slicing machine as claimed in claim 8, 10 in which the flexible means therein defined comprises a plurality of endless members arranged one above the other.

10. A slicing machine comprising a frame, a rotatable knife mounted on said frame, a gauging abutment, said abutment comprising a support mounted on said frame adjacent said knife for relative and constrained movement to and from the plane of the knife, adjusting means mounted on the frame and operatively connected with the support to permit adjustment of the abutment to and from said plane of the knife, a carriage for supporting the substance for reciprocatory movement past said abutment and across the cutting edge of the knife, said support comprising an abutment frame, rolls journaled in said abutment frame, flexible means supported by said rolls in a plane substantially parallel with that of the knife, and feeding means on the carriage for feeding substance in direct abutment with said flexible means to accurately gauge the thickness of the slice and to cause the said substance to frictionally engage the surface of the flexible means and cause said last named means to move with the substance toward the knife during said reciprocatory movement.

11. The combination with a slicing machine having a rotary knife, a substance support arranged for relative reciprocation in regard to the knife, feed means for feeding substance

across the support toward the cutting plane of the knife, a gauge plate at one side of the knife slicing plane and against which the substance is abutted by the feed means and in contact with the gauge plate so as to cut a slice of a predetermined thickness from the substance, means for moving the gauge plate toward and away from the slicing plane of the knife so that slices of different thicknesses may be cut by the knife from the substance, and movable means on the gauge plate, said last named means being movable by the movement of the substance during relative movement of the support when the substance on the support is in a position opposite the gauge plate and forced into contact with the gauge plate by the feed means whereby to overcome friction between the substance and the gauge plate and prevent bleeding of the substance.

12. The combination with a slicing machine 20 having a rotary knife, a substance support arranged for relative reciprocation in regard to the knife, and feed means for feeding the substance across the support toward the cutting plane of the knife, of a vertical gauge plate positioned at one side of the cutting plane of the knife to gauge the thickness of the slice to be cut from the substance and against which the substance is abutted by the feed means prior to the cutting operation, and movable means on the gauge plate and movable by the frictional engagement of the substance abutted thereagainst during slicing movement by the relative movement of the support whereby the substance will slide freely over the movable means toward cutting position and rubbing of the substance against the gauge plate is overcome.

CORNELIS FRANCISCUS

MARIA VAN BERKEL.
